UNITED STATES PATENT OFFICE.

DAVID F. HUNT, OF ANTRIM, NEW HAMPSHIRE, ASSIGNOR OF ONE-HALF TO
HOWARD P. ELWELL, OF GLOUCESTER, MASSACHUSETTS.

MACHINE FOR WINDING THREAD ON SPOOLS.

SPECIFICATION forming part of Letters Patent No. 503,086, dated August 8, 1893.

Application filed September 3, 1892. Serial No. 444,947. (No model.)

To all whom it may concern:

Be it known that I, DAVID F. HUNT, of Antrim, county of Hillsborough, State of New Hampshire, have invented an Improvement in Machines for Winding Thread on Spools, of which the following description, in connection with the accompanying drawings, is a specification, like letters and figures on the drawings representing like parts.

10 This invention has for its object to simplify and improve the construction of that class of machines adapted to wind thread on spools of commerce. In this class of machines it has been customary to provide devices for insuring a definite number of traverse strokes of the traverse mechanism for a spool of a given size and thread of a given number, and the number of strokes having taken place, the winding has been stopped automatically. In 15 other machines the thread-laying finger of the traverse mechanism has had combined with it a device to contact with the beveled inner sides of the spool heads, and by devices intermediate it and the screw shafts change 20 the half nuts automatically for each traverse, the traverse being gradually longer and determined by the length of the space to be 25 filled. My invention relates to this latter class of machines.

30 One part of my present invention consists in effecting the reversal of the thread traversing mechanism automatically by the direct contact of the thread guiding finger of the traverse mechanism onto the inclined inner ends of the spool heads, said finger being 35 rigidly attached to one end of a rock shaft provided with suitable wings which as the said rock shaft is turned by the contact of said finger with the spool, effects the necessary movements of the half nut carrying 40 frame, and causes first one and then the other of said half nuts to engage the right and the left hand threaded parts of the said shaft and effect the desired direction of movement of the 45 traverse mechanism for the desired distance. This rock shaft in this present embodiment of my invention is also made vertically movable so as to enable the under side of the thread-laying finger to act directly on the 50 surface of the thread being wound in layers on the spool, said rock shaft having at its

lower end a piston filling a cylinder or chest containing preferably mercury, oil, or other suitable liquid not easily evaporated, the piston being provided with a suitable valve-controlled passage or passages to enable the liquid to pass from the upper to the lower side of the piston with such slowness as to prevent any tendency of the thread-laying finger jumping or trembling under the action of the 55 thread leading it and being laid on the spool rotated at high speed. I have so proportioned the passages and valves referred to that the downward movement of the piston and rock shaft may be made more quickly, as when a 60 spool is to be removed and another applied between the spool holding apparatus. I have provided the rock shaft with an actuating device to contact with part of a stop motion and stop the rotation of the spool when filled, 65 said stop mechanism in this my present invention co-operating with a friction brake to be described.

Figure 1, in perspective shows a thread-winding machine having my improvements 70 applied to it. Fig. 1^a, shows the shipper lever detached; Fig. 1^b, part of the lever 5 and the link 6. Fig. 2, is a detail showing the thread-laying finger, its rock shaft, cylinder, half nut carrying frame, and actuating device viewed 75 from the side opposite that shown in Fig. 1; Fig. 3, a detail in section of the cylinder and piston; Fig. 4, a detail of the end of the arm; and Fig. 5, a sectional detail of one of the two like chucks for holding the spool. 80

The frame-work of the machine consists 85 essentially of end pieces A united by cross girths A¹, A², the girth A² having a stand A³ erected upon it, said stand containing suitable bearings for a shaft A⁴ which imparts motion 90 to the spool a, to be wound with thread. The forward end of the shaft A⁴ has a suitable screw thread, see dotted lines, Fig. 5, upon which is secured a spool-holding clutch A⁵ made of a longitudinally fluted block having 95 a series of spurs 2, said block entering a collar A⁶, the edges of the flutes extending back to or beyond the face of the collar and getting a good hold upon the spool. Making the chuck of a fluted piece and an independent 100 collar enables the edges of the flutes to be extended back to or beyond the collar, which

could not be done economically if the collar and fluted piece were all in one.

The shaft A⁴, called the spindle shaft, has fast upon it a brake pulley b surrounded by 5 a suitable band b', one end of which is fixed to the stand A³, the other end being acted upon by a projection b³ of a belt shipper b⁴ pivoted at b², said band when closed upon the brake pulley by the movement of the said 10 belt shipper acted upon by a spring b⁷ serves to instantly stop the rotation of the spindle, as will be described. But very slight strain on the band b' is sufficient to enable it to act as a brake on the pulley b. The shipper b⁴ turns in the arc of a circle about the center 15 b². The hub of the brake pulley is shown as having a suitable belt pulley b⁵, to receive a suitable belt, not shown, driven from some suitable countershaft, not shown, and along- 20 side of this pulley there is loose upon the shaft A⁴ a pulley b⁶ also suitably grooved to receive the said belt when the spindle is at rest. The belt shipper b⁴ has a suitable fork b⁸, see Fig. 1^a, to receive and guide the belt 25 referred to from one to the other of the pulleys, a spring b⁷ normally acting to move the shipper and put the belt upon the loose pulley. The shipper handle has extended upwardly from it a projection b⁸ which is en- 30 gaged by a latch b⁹ connected to a rock shaft b¹⁰ mounted in suitable bearings on the stand A³ containing the spindle shaft, said latch being acted upon by a spring b¹² to keep it 35 in engagement with the projection b⁸ of the shipper lever to hold in place with the driving belt on the fast pulley b⁵. The rock shaft b¹⁰ has a depending leg b¹³, see Fig. 1, provided at its lower end with a regulating device b¹⁴, shown as a lever pivoted at b¹⁵ and having 40 one end normally weighted to contact with an adjusting device shown as a screw b¹⁶, the adjustment of said screw putting the opposite end of the said regulating device in one or another position so as to be struck sooner 45 or later by a lug as b¹⁷ on a feeler rod d, to be described, said regulating device when struck by said lug causing the shaft b¹⁰ to be turned sufficiently to enable the latch b⁹ to release the belt shipper and effect the stopping of the 50 machine. The lower end of the rod d is fixed to the actuating device c⁵ and to enable it to follow the actuating device in its movements the lug d³ projecting from the carriage 20, see Fig. 1, is slotted to permit the said rod to 55 move with the actuating device, the distance of the movement of the rod with the actuator being but slight owing to the slight movement necessary to enable the actuator to control the half-nuts. 60 In practice, the stand A³ will have pivoted upon it at one side of it near its upper end a drop wire as b¹⁸, so that when the thread going to the thread-laying finger c breaks, the short arm of the drop wire will act against 65 the under side of the latch b⁹ and lift it to disengage the projection b⁸, and stop the machine.

The spindle shaft has, as represented, at its outer end a cone pulley b¹⁹, which, by suitable straps b²⁰ extended over a drum b²¹, rotates the screw shaft b²², provided for about one half of its length with a right-hand screw, and for the other half of its length with a left-hand screw. 70

The stand A³ has a suitable ear 3 through which is extended a slide-rod 4 connected with a handle 5 pivoted upon a link 6 pivoted at 7 on a stand fixed to the frame-work, see Fig. 1^b. This slide-rod has connected to it the tail stock B of the machine, said tail stock 80 having a suitable centering device as B', preferably of the same construction as that at the end of the spindle, to enter the spool. The tail stock may be moved back and forth by the handle referred to, to adapt it to the 85 length of spool required.

The slide rod has fast upon it a cam bar B² having cam surfaces 10, 12, and a lug 13, said cam surfaces acting against adjustable fingers 14, 15, attached to the rocking frame B⁴ carrying the half nuts 16, 17, one or the other of which is to be kept in engagement with one of the threads of the screw shaft, except when the traverse mechanism is to be moved by hand, and when this is to be done, the cams 10, 95 12, by acting against the fingers push the lower end of the traverse frame away from the screw shaft sufficiently to remove both half nuts from the screw-threads. 90

I will now describe the traverse mechanism. 100 The stand A³ and the tail stock each have a suitable bearing as 18, 18^x, which receive a slide rod 19 upon which is fastened by suitable set screws a carriage 20 having a tubular vertical bearing portion B³ and a lug B⁵, the portion B³ receiving a rock shaft c' having fixed to it near its upper end the thread-laying finger c, before described, over which is led in a suitable groove therein the thread to be wound upon the spool, the said thread 110 coming from the thread guide b¹⁸ referred to, through an eye c² at the upper end of the rock-shaft. The slide rod 19, the carriage 20 attached thereto and having a vertical bearing B³ and an ear B⁵, constitute what I 115 designate a slide or traverse frame, it being adapted to slide longitudinally first in one and then in the opposite direction and carrying with it the rock-shaft c' to be described, the said rock-shaft having attached to it the thread-laying 120 finger c. The lug B⁵ of the carriage referred to receives a stud screw B⁶, the lower end of which is screwed into a threaded ear B⁷ of the cylinder or dash pot B⁸, the upper end of the stud screw being held in place by a nut B⁹. 125 This stud screw supports and suspends below the carriage the cylinder referred to, which in practice, will be filled with mercury, oil, or other fluid F, see Fig. 3, not easily evaporated. The stud screw referred to forms the pivot 130 for the frame B⁴ carrying the half nuts 16, 17. The half nut frame B⁴ in this present embodiment of my invention, carries an arm B¹⁰ which engages one or another cam notch 135

200, see Fig. 4, in the end of a rigid arm B^{20} shown as connected to the cylinder B^8 , said arm holding the half nut frame in one or the other of its extreme positions. The rock-shaft c' referred to, has fast upon it an actuating device c^5 for the half nut carrying frame, said actuating device having, as shown, see Fig. 2, two depending fingers 201 adapted to act upon adjustable blocks 202 mounted upon the half nut carrying frame, said blocks being adjustable to thus compensate for wear and obviate any possible lost motion. The lower end of the rock shaft c' has fast upon it a piston c^6 , see Fig. 3, provided, as represented in Fig. 3, with two passages c^7 , c^8 , one closed at its upper end with a valve c^9 and the other at its lower end with a valve c^{10} , the spring c^{20} controlling the valve c^9 at the top of the piston being weaker than the spring c^{21} at the bottom of the piston in order that the oil or other liquid may have a more ready passage from the under side of the piston to its upper side than vice-versa. This piston by resting in the body of oil or mercury, or equivalent acting-liquid, as described, positively obviates any jumping motions of the thread guiding finger c resting directly upon the strand of thread being laid in layers upon the spool, it being remembered that the spool is being rapidly rotated and that uneven or hard portions in the thread would have a tendency to make the thread-laying finger jump or tremble were it not for the piston referred to. The actuating device c^5 referred to, carries a feeler rod d upon which is adjustably secured the lug b^{17} before referred to, which lug, during reciprocation of the traverse mechanism to the left, viewing Fig. 1, meets the controlling device b^{14} and stops the rotation of the spindle, as described, when the spool has been filled to exactly the proper point, this lug being certain in its action when the mass of thread has reached the desired diameter, the lug being adjustable for spools of different sizes and threads of different counts. I have also in this instance of my invention shown the said rod as provided with a stop device d^2 which may be adjusted to the work to be done so that when the thread has been wound to make the spool of proper diameter, or so as to contain the desired number of yards, the said stop device will meet the projection d^3 of the traverse mechanism, and prevent any further rise of the rock-shaft c and its thread-laying finger c' , which would allow the said finger to pass beyond the head, thus destroying the value of that spool of thread. Referring to the spool a , it will be seen that the inner sides of its heads are inclined or beveled as at a' , and I use these beveled surfaces to determine the length of each traverse. I am enabled to so use these beveled sides by or through the employment of the rock-shaft c' upon which I have fixed or secured the thread-laying finger c , it being understood that, as soon as the thread-laying finger contacts with the bevel-

eled portion of the spool,—the carriage being moved to the right or left by the screw-shaft,—the said finger will be momentarily arrested while the carriage 20 continues to travel sufficiently to rock the shaft c' and cause it by its attached actuating device c^5 to turn the half nut carrying frame B^4 quickly in one or the other direction so as to remove one half nut from one screw thread and put the other half nut in engagement with the other screw thread, which quickly reverses the movement of the traverse mechanism. This operation is continued each traverse being longer and longer until the maximum traverse is reached, *i.e.*, until the thread-laying finger arrives at nearly the level of the periphery of the spool head, at which time the lug b^{17} carried by the rod d which was lifted in unison with the rock shaft c' , comes opposite the controlling device b^{14} forming part of the stop motion before described, and actuates the stop motion to effect the stopping of the rotation of the spindle. Now, if for any reason, as when the operator desires to put the thread-laying finger in any particular position with relation to the spool, or to cause a half nut to engage any particular portion of the threads of the screw shaft, as may be the case sometimes after a thread has been broken and the operator desires to reset the machine to resume operations, the operator may engage the cylinder by hand and pull it away from the screw shaft, a spring f connected with the cylinder and bearing on the rear part of the rod A' at such times yielding sufficiently to let the half nuts be disengaged from the screw shaft. When the tail stock is drawn fully to the right in Fig. 1 by or through the hand lever 5, then both the half nuts are disengaged from the screw shaft by or through the cam bar B^2 thus leaving the operator free to move the traverse more or less in any desired direction to properly place the thread-laying finger in proper position for the work to be done.

Having thus described my invention, what I claim as new, and desire to secure by Letters Patent, is—

1. In a machine for winding thread, a rotatable spindle to rotate a spool having the inner sides of its head inclined; a screw shaft; a pivoted frame having half-nuts at its opposite ends to co-operate with said screw shaft; a pivot for said frame, said pivot being located at right angles to the center of rotation of the screw shaft; a slide-frame having bearings for said pivot; combined with a sliding and rocking rod c' arranged in bearings in said slide frame and occupying a position substantially at right angles to the center of rotation of the screw shaft, and a thread-laying finger, and an actuating device, both fixed to said sliding and rocking rod said actuating device being adapted to act upon and shift the half-nut carrying frame whenever, in the movements of the sliding frame, the thread-laying finger attached to said sliding and

rocking shaft contacts directly with the beveled inner face of one of the heads of the spool, to thus partially rotate said sliding and rocking shaft, substantially as described.

- 5 2. In a thread winding machine, the following instrumentalities, viz;—a rotating spindle to rotate the spool to receive the thread, a rock shaft having a fixed thread-laying finger and provided at its lower end with a piston 10 and also with an actuating device; a traverse frame in which said rod is mounted, a cylinder containing a fluid through which the said piston is adapted to be moved, a rotating screw shaft and a frame carrying half nuts, the said frame being turned in one or the other direction by the actuating device connected with the said rock shaft whenever the thread laying finger comes directly in contact with the head of the spool, substantially as 20 described.

- 15 3. The combination with the rotating spindle and horizontal sliding traverse frame, of a vertically movable rod having fixed to it a thread laying finger and also a piston, combined with a cylinder containing a liquid in which said piston is immersed to thereby obviate jumping of the thread carrying finger on or with relation to the mass of thread being wound, substantially as described.

- 25 30 4. A rotating spindle adapted to carry a spool upon which thread is to be wound; a vertically movable rod having an attached thread laying finger; a rod as d moved in unison therewith and provided with a lug; a belt shipper; a frame in which said rods reciprocate at right angles to the length of the spool; and means to reciprocate said frame; combined with stopping mechanism acted upon by the said lug when the spool has been filled 35 with thread, substantially as described.

- 40 45 5. A rotating spindle to carry a spool, a traverse frame, a vertically movable rod therein having a fixed thread laying finger, combined with a device movable in unison with the said rod and adapted to arrest its upward motion when a predetermined quantity of thread has been wound upon the spool, substantially as described.

- 50 55 6. A rotating spool-carrying spindle, a fast and loose pulley thereon, a belt shipper, a stopping mechanism consisting of a latch and an arm provided with a controlling device, said controlling device being adjustable; combined with a vertically movable rod d having a lug which is gradually raised as the mass of thread increases in diameter upon the spool until the predetermined amount of thread having been wound upon the spool, the said lug meets the said controlling device 60 and effects the stopping of the machine, substantially as described.

- 65 7. In a spool-winding machine, the shipper; stop mechanism co-operating with said ship-

per and provided with an adjustable regulating device; combined with a traverse mechanism, a lug as b^17 moved in unison with it, and devices to move the lug toward the plane occupied by the end of the regulating device whereby when the desired length of thread has been wound, the said lug strikes the regulating device and effects the release of the shipper so that it may move and cause the machine to be stopped, substantially as described.

- 70 75 8. In a machine for winding thread on commercial spools, a spindle to rotate a spool; a screw shaft; a sliding or traverse frame having a pivot, a frame, as B^4 , mounted on said pivot and provided with half nuts and with adjustable ears 202, combined with a rod c' 80 mounted in said frame and adapted to both slide and rock therein, a thread-laying finger attached to one end of said rod, and an actuating device attached to the other end of said rod, said actuating device being adapted to 85 strike the said ears when the thread-laying finger contacts with the spool heads to operate the frame carrying the said half nuts, as and for the purpose set forth.

- 90 95 9. In a machine for winding thread on commercial spools, a spindle to rotate a spool; a screw shaft; a sliding or traverse frame having a pivot; a frame, as B^4 , mounted on said pivot and provided with half nuts and ears 202; a rod c' mounted in said frame and 95 adapted to both slide and rock therein; a thread-laying finger attached to one end of said rod, and an actuating device attached to the other end of said rod, said actuating device being adapted to strike said ears when the thread laying finger contacts with the spool heads to operate the frame carrying the said half nuts, combined with a locking device consisting of a spring and of a notched arm, substantially as described.

- 100 105 10. In a machine for winding thread on spools of commerce, a shaft having right and left hand screw threads, means to rotate said shaft, a slide or traverse frame, a stud B^6 mounted therein, the frame B^4 adapted to turn about said stud and provided with half nuts, and having adjustable fingers 14, 15, combined with a slide rod having an attached cam bar B^2 provided with cam surfaces to co-operate with said pivoted frame, and a spring 115 f to normally hold the said fingers pressed toward the said cam bar B^2 , substantially as described.

In testimony whereof I have signed my name to this specification in the presence of 120 two subscribing witnesses.

DAVID F. HUNT.
